CLAIM

The ornamental design for a necklace separator as shown and described.

DESCRIPTION

FIG. 1 is a top view of the necklace separator according to my new design;

FIG. 2 is a bottom view thereof;

FIG. 3 is a left side view thereof;

FIG. 4 is a front view thereof;

FIG. 5 is a right side view thereof;

FIG. 6 is a rear view thereof; and,

FIG. 7 is a top, front, and right side perspective view thereof. The broken lines are shown for the purpose of illustrating both parts of the article as well as boundaries of the claimed design, wherein none of the broken lines form part of the claimed design.
